Primary Examiner — Kevin Rudzinski(74) *Attorney, Agent, or Firm* — Mitchell Law PLLC; Matthew W. Mitchell(57) **CLAIM**

The ornamental design for an indoor plant growing apparatus, as shown and described.

DESCRIPTION

FIG. 1 is an isometric view of the indoor plant growing apparatus of the present invention;

FIG. 2 is a front view of the indoor plant growing apparatus of FIG. 1;

FIG. 3 is a rear view of the indoor plant growing apparatus of FIG. 1 as seen from a bottom side of FIG. 2;

FIG. 4 is a side view in elevation of the indoor plant growing apparatus of FIG. 1, as seen from the left side of FIG. 2;

FIG. 5 is a side view of the indoor plant growing apparatus of FIG. 1, as seen from the right side of FIG. 2; and,

FIG. 6 is a top view of the indoor plant growing apparatus of FIG. 1.

The broken line showing a capping structure is included for contextual purposes and forms no part of the claimed design.
